UNITED STATES PATENT OFFICE.

JOHN DEAM KNEEDLER, OF SIOUX CITY, IOWA, ASSIGNEE OF ONE-HALF TO BUEL COUCH, OF SIOUX CITY, IOWA.

ROTARY ENGINE.

1,142,969.

Specification of Letters Patent. Patented June 15, 1915.

Application filed May 2, 1914. Serial No. 835,974.

To all whom it may concern:

Be it known that I, JOHN DEAM KNEEDLER, a citizen of the United States, residing at Sioux City, in the county of Woodbury and State of Iowa, have invented certain new and useful Improvements in Rotary Engines; and I do hereby declare the following to be a full, clear, and exact description of the invention, such as will enable others skilled in the art to which it appertains to make and use the same.

This invention relates to rotary engines and more particularly to that class of rotary engines known as the convertible type, and has for one of its objects the construction of a rotary engine which may be operated through the medium of explosive fuel, steam, compressed air or water.

A further object of this invention resides in the construction of a rotary engine which may be operated through the medium of any of the well known elements for creating power and at the same time can be used as an air compressor or water pump, or by connecting the engine to another engine my invention may be efficiently used as an engine starter.

A still further object of this invention is the provision of a rotary engine which is capable of being readily converted into a number of useful machines without the necessity of making any alterations therein.

Another object of this invention resides in the provision of means for alternately drawing in a fuel charge, compressing the same and firing the charge at the point of greatest compression when the engine is used as an explosive engine. And a still further object of the invention resides in the provision of means, for storing power and subsequently utilizing the same as a motive power for starting the engine. And still another object of this invention resides in the provision of means whereby a plurality of explosions are obtained at each revolution of the driving shaft thus greatly increasing the power of the engine.

These and other objects will more fully appear and the nature of the invention more clearly understood by the construction, combination and arrangement of the parts thereof as described in the following specification, defined in the appended claims and

illustrated in the accompanying drawings, in which,

Figure 1 is a front view of the engine, with the front cover plate removed showing the relative mounting of the working parts within the engine. Fig. 2 is a vertical longitudinal sectional view on line 2—2 of Fig. 1 looking in the direction of the arrows showing the working parts in operative position and the means for operating the same.

For the sake of convenience and clearness the invention will be described as an explosive engine, though it is to be understood that the same may be also used as an air or steam engine, air compressor, pump or engine starter if so desired.

Referring to the drawings 1 denotes the bed of the engine upon which is mounted the cylindrical rotor casing 2 provided with the integral rear plate 3, and at the front end of the cylindrical casing 2 is formed the flanges 4, and in which flanges 4 and the bed 1 is formed a plurality of internally screw threaded apertures 5 for receiving the securing bolts of the front plate to the hereinafter described. The rotor casing 2 is provided upon the top portion with the base 6 and at the right hand side thereof is formed the boss 7, through which and the wall of the rotor casing 2 is formed the exhaust port 8, and screw threaded or otherwise connected to the boss 7 is the exhaust pipe 9 for conveying the exhaust products which pass through the exhaust port 8 to any point of delivery.

At the lower left hand side of the rotor casing 2 and adjacent the bed 1 is formed the boss 10 through which and the rotor casing 2 is formed the outlet port 11, and connected to the boss 10 in any suitable manner is the check valve 12 to which is secured the pipe 13 for conveying fluid which has been compressed in the lower part of the rotor casing 2 to a storage tank, (not shown), for storing the compressed fluid for subsequently utilizing the same as power, preferably used for the initial starting of the engine.

Formed in the upper portion of the rotor casing 2 and through a portion of the base 6 is the inlet port 14 to which is connected the valve 15 and suitably secured to the valve 15 is the pipe 16, the pipe 16 being

- connected in any desirable manner to either a steam boiler (not shown) or to a compressed air reservoir (not shown), or to both, if so desired, it being understood that suitable branch pipes and valves necessary for such connections may be used for supplying steam or compressed air to the port 14 as a motive power for running the engine when it is desired to convert the same into a steam engine or a compressed air motor.
- Arranged upon the base 6 of the rotor casing 2 is a housing comprising the side walls 17 and the rear wall 18, the lower edges of the walls 17 being provided with laterally extending flanges 19 through which pass the retaining screw bolts 20 for securing the housing upon the base 6. The front ends of the side walls 17 of the housing are provided with the internally screw threaded apertures 21 for the reception of the securing bolts of the front plate. The housing is further provided with the top 22 secured to the side walls 17 and the rear wall 18 by the screw bolts or other suitable fastening means 23, and formed upon the top 22 is the elongated hood 24 providing a fuel chamber 25, the hood 24 being positioned approximately centrally of the top 22 but extending from the rear to the front thereof, and formed upon the hood 24 is the boss 26 to which is connected the union 27 connected with the pipe 28, the pipe 28 having secured upon the opposite end the valve 29, the valve 29 having connected therewith the fuel supply pipe 30, which leads to the carburetor (not shown), the fuel charge being drawn through the pipes 30 and 28 into the fuel chamber 25 by suction in a manner to be hereafter described.
- The front of the rotor casing 2, the housing arranged thereon and the fuel chamber 25 are all closed by the front plate 31, the plate 31 being of the exact configuration of the outlines of the rotor casing 2, the housing and the fuel chamber and secured thereto through the medium of the screw bolts 32 engaging the screw threaded apertures 5 and 21 of the casing and housing respectively. The front plate 31 is provided with the laterally extending lower arm 33 having arranged upon the end thereof the bearing 34. The plate 31 is also provided with the laterally extending upper arm 35 provided with the bearing 36.
- Formed upon the front plate 31 and arranged in eccentric relation to the rotor casing 2 is the bearing 37, and also arranged upon the rear plate 3 of the rotor casing 2 is the bearing 38 being also arranged in eccentric relation to the rotor casing 2 and correspondingly opposite to the bearing 37 of the front plate 31.
- Within the rotor casing 2 is arranged the hub 39 of the rotor having one end slightly reduced as at 40 and suitably journaled

within the journal box 38 of the rear wall 3, the hub 39 having its opposite end also reduced as at 41 and suitably journaled within the journal box 37 of the front plate 31, the reduced end 41 of the hub 39 projecting for a distance beyond the exterior surface of the front plate 31 and having arranged upon the end thereof the gear wheel 42 fixedly secured to the reduced end 41 through the medium of the screw bolt 43 whereby the gear wheel 42 and the hub 39 of the rotor rotate in unison.

Extending entirely through the hub 39 and the reduced end portions 40 and 41 is the driving shaft 44 provided with the key 45 for engaging the elongated groove 46 formed in the interior wall of the bore of the hub 39, the groove 46 extending the entire length of the hub 39 within the casing and the reduced end portion 40 thereof, this construction providing for the ready passage of the shaft 44 through the hub 39 of the rotor and allows the shaft 44 to be longitudinally slidable within the hub 39 but by the provision of the key 45 and the groove 46 provides for the rotation of the shaft 44 by the rotor. The rotor is formed with the hollow cylinder 46 extending the full length of the rotor casing 2 and extending from the cylinder 46 radially to the hub 39 are the plates 47, these plates being arranged in pairs and spaced apart to provide the guide ways 48 therebetween, the cylinder 46 being provided with the longitudinal opening corresponding with the spaces 100 forming the guide way 48, and within each of the guide ways 48 and between each of the pairs of the radial guide plates 47 are the piston blades 49, the blades 49 being provided with the longitudinal grooves 50 in the outer ends thereof and into which grooves are snugly seated the wear plates 51. At each end of the piston blades 49 adjacent the inner edge thereof are arranged the pins 52. The pins at one end of the piston blades 49 travel in the circular groove 52' formed in the rear plate 3 of the rotor casing 2, while the pins at the opposite ends of the piston blades 49 travel in the circular groove 53 formed in the disk 54 which disk 54 is of the exact diameter of the exterior diameter of the cylinder 46 of the rotor and is seated within the circular recess 55 formed in the inner wall of the front plate 31 and retained within the recess 55 through the medium of the screw bolts 56, the disk 54 being provided with the peripheral groove 57 into which is seated the packing ring 58.

It is to be noted that the rotor is eccentrically mounted relative to the rotor casing 2 and that the disk 54 is seated within the front plate 31 concentric with the rotor but also eccentric relative to the rotor casing 2, and this mounting of the rotor provides

the approximately crescent shape pressure chamber 59, and it is to be further noted that the circular groove 52' formed in the rear plate 3 and the circular groove 53 formed in the disk 54 are arranged correspondingly opposite each other and concentric relative to the rotor casing 2 but eccentric relative to the hub 39 of the rotor and the driving shaft 44 whereby the pins 52 at the ends of the piston plates 49 cause the piston blades 49 to travel inwardly and outwardly within the space 48 between the radial plates 47 so that the piston blades 49 are forced gradually outwardly during the rotation of the rotor at the pressure chamber side of the rotor but are gradually drawn inwardly when the piston blades 49 reach the opposite side of the rotor chamber 2 and thus the wear plates 51 are held constantly in contact with the inner circular wall of the rotor casing 2 during the rotation of the rotor, the piston blades 49 receiving the pressure of the motive fluid within the pressure chamber 59 when the blades 49 are forced outwardly by the pins 52 traveling in the grooves 52' and 53 respectively.

Within the inner wall of the rotor casing 2 opposite the pressure chamber 59 is formed the arcuate cutout portion 60, the arc of this cutout portion 60 being of a length equal to the radius of the rotor and of a curvature equal to that of the circumference of the cylinder 46 of the rotor whereby that portion of the cylinder 46 adjacent the arcuate cutout portion 60 is designed to be snugly seated therein for preventing the fluid or pressure within the pressure chamber 59 from passing around the rotor, the rotor however, being positioned relative to the arcuate cutout portion 60 in a manner whereby the same may readily rotate therein.

Mounted within the housing arranged upon the base 6 of the rotor casing 2 is the cylinder 61 provided with the exterior side ribs 62, and also with the lower parallel ribs 63 and the upper parallel ribs 64, the ribs 62 firmly engaging the wall 17 of the housing, the ribs 63 firmly engaging the upper surface of the base 6, and the upper ribs 64 engaging the top 22 of the housing and the space between the respective ribs and the walls and top of the housing and the base 6 provides the water jackets 65, the ribs 62 being provided with the vertical channels 66 for establishing communication between the upper and lower water jackets 65.

Formed in the base 6 of the rotor casing 2 are the ports 67 for communicating with the lower valve chamber 68 formed between the lower parallel ribs 63 of the cylinder 61, and formed in the bottom wall of the cylinder 61 are the ports 69 for establishing communication between the lower valve

chamber 68 and the cylinder 61, and arranged in the upper wall of the cylinder 61 are the ports 70 for establishing communication between the cylinders 61 and the upper valve chamber 71 formed between the upper parallel ribs 64 of the cylinder 61, and also formed in the top 22 and within the hood 24 are arranged the ports 72 for establishing communication between the upper valve chamber 71 and the fuel chamber 73.

Arranged within the cylinder 61 is the piston 73 operated by the piston rod 74 projecting through the stuffing box 75 of the front plate 31, the piston rod 74 also projecting beyond the piston 73 and passes through the rear wall 18 of the housing and has arranged upon the extremity thereof the piston 76, the piston 76 operated within the air compressor cylinder 77, the cylinder 77 being provided with the annular flange 78 through which flange passes the bolts 79 for securing the air compressor cylinder 77 upon the wall 18 of the housing. The air compressor cylinder 77 is provided with the valve housing 80 in which is seated the valve 81 for closing the inlet port 82 formed in the valve housing, the port 82 being provided with the outer cap 83 which is manually operated through the medium of the handle 84. Arranged in one side of the compressor cylinder 77 is the outlet port 85 leading into the valve housing 86 provided with the valve 87 and connected to the valve housing 86 is the discharge pipe 88 leading to a compressed air reservoir (not shown).

For reciprocating the pistons 73 and 76, the piston rod 74 is pivotally connected as at 89 to the link 90 connected to the crank 105 91 of the timing shaft 92 journaled in the bearings 34 and 36 of the arms 33 and 35 respectively of the front plate 31, and arranged adjacent the lower end of the shaft 92 is the bevel gear 93 for meshing with the gear 42 through which connections the shaft 92 is revolved.

Within the lower valve casing 68 is the slide valve 94 provided with the valve rod 95 projecting through the front plate 31 and having arranged upon its free end the wear plate or button 96 for engaging the cam 97 arranged upon the shaft 92, and also arranged within the upper valve casing 71 is the slide valve 98 provided with the valve rod 99 projecting through the front plate 31 and having arranged upon the free end thereof the wear plate or button 100 for engaging the cam 101 also arranged upon the shaft 92. For maintaining the wear plate or button 96 of the valve rod 95 in constant engagement with the cam 97 is provided the compression spring 102 interposed between the front plate 31 and the wear plate 96 and for maintaining

the wear plate 100 of the valve rod 99 in constant engagement with the cam 101 is provided the compression spring 103. Each of the valves 94 and 98 are provided with 5 the oil pockets 104.

The interior of the cylinder 61 at each side of the piston 73 provides the compression chamber 105 and 106 and arranged in the wall of the cylinder 61 and one of the 10 side ribs 62 is the spark plug 107 for the compression chamber 105 and also the spark plug 108 for the compression chamber 106, the spark plug 107 being connected in circuit by the wires 109 with the contacts 110 15 of the timing mechanism 111 arranged upon the upper end of the timing shaft 92, the spark plug 108 being also electrically connected by the wires 112 with the contacts 113 of the timing mechanism 111 the arm 20 35 being provided with the extension 114 for supporting the contacts 110 of the timing mechanism; however, the timing mechanism may be of any of the usual constructions now in use.

25 When my engine is to be used as an explosive engine, the engine is initially started by opening the valve 15 for allowing steam or compressed air to pass through the port 14 into the pressure chamber 59 30 for operating the piston blades 49 for rotating the rotor and the shaft 44 in the direction of the arrow and through the gear connections 42 and 93 the shaft 92 is rotated in the direction of the arrow. This 35 movement of the shaft 92 operates the crank 91 and through the connections of the piston rod 74 the piston 73 is reciprocated within the cylinder 61, the piston 73 performing the functions of drawing in a fresh 40 supply of fuel at one side thereof, and compressing the previously drawn supply of fuel at the opposite side thereof during its movement in one or the other direction. Taking the position of the parts as shown 45 in Fig. 2 as an example of the first operation, it will be conceded that a charge has been previously drawn into the compression chamber 105 the same having been drawn in by the suction created by a former stroke 50 of the piston 73 to the right through the ports 70 and 72 from the fuel chamber 25, and which charge was also drawn through the pipe 28 and 30 from the carburetor, the valve 98 in this instance being at the right 55 of the valve chamber 71. The fuel being now contained in the compression chamber 105 under compression, the left hand ports 69 and 67 being opened by the movement of the valve 94 to the right which at this 60 movement of the valve the spark 107 through its connections with the timing mechanism explodes the fuel charge, the force of which passes through the ports 69 and 67 into the pressure chamber 59 of the 65 rotor casing thereby exerting pressure

against one of the piston blades 49 which has just passed the port 67, the left hand ports 70 and 72 being closed by the left movement of the valve 98 just prior to the explosion prevents the passage of the explosive charge from passing backward into the fuel chamber 25. There being at this time a fresh charge drawn in the compression chamber 106 through the right hand ports 70 and 72 from the fuel chamber 25 caused by the vacuum or suction created by the piston 73 in its movement to the left, the right hand ports 69 and 67 being closed by the right hand movement of the valve 94 and upon the next movement of the piston 73 to the right, the fresh fuel charge in the compression chamber 106 is thereby compressed and exploded as in the manner above described relating to the compression chamber 105, and the operation alternately 85 and continuously repeated during the running of the engine. Should it be desired to also operate the engine as a compressor the cover plate 83 is swung around by the handle 84 thereby opening the port 82 to the atmosphere whereby the suction caused by the movement toward the left of the piston 73 will draw air within the cylinder 77 forcing the valve 81 inwardly, the valve 87 being closed and upon movement of the piston 76 toward the right the valve 81 will necessarily close and the valve 87 will be moved outwardly whereby air will be forced outwardly through the port 85 and the pipe 88 to the compressed air reservoir or other suitable means for storing air under pressure. Should it be desired to use this portion of the engine structure for a water pump instead of an air compressor, it is only necessary to connect the port 82 with 100 a pipe leading to a supply of water and pumping the water into the cylinder 77 and forcing the water outwardly through the discharge pipe 88 to a tank or any other means or point of use. Should it be desired also to use my invention as an air, steam or water motor, the gear 42 is disconnected from the reduced portion 41 of the rotor hub 39 and brought out of engagement with the gear 93, the pipe 16 being connected in 105 any suitable and efficient manner with a compressed air reservoir, steam boiler or hydraulic pressure, the valve 15 is then opened and in this instance the air, steam or water, whichever is preferred, passes 110 through the port 14 into the pressure chamber 59 and thus forces the piston blades 49 downwardly within the pressure chamber 59 whereby the rotor and the driving shaft 44 are rotated.

125 Whether the engine is used as an explosive engine, steam, air or water motor, there is always a certain portion of fluid in the lower portion of the pressure chamber 59 in front of the piston blades 49 which is 130

5 compressed and forced outwardly through the port 11 pass the check valve 12 and conveyed by the pipe 13 to any suitable form of storage tank for storing a certain portion of the power to be subsequently utilized in starting the engine.

I desire to here state that while I have shown 4 piston blades whereby I may be enabled to obtain 4 explosions to each revolution of the driving shaft 44, this being further accomplished by the ratio of the gear wheels 42 and 93, in this instance the ratio being 4 to 2, I do not limit myself to this exact number of piston blades 49 or 10 to the ratio of the gear wheels as a greater or less number of piston blades may be used to meet the exigencies of the case.

While I have here shown and described the preferred embodiment of my invention 20 I hereby reserve the right to make such alterations and variations therein from time to time as I may deem expedient and which will neither depart from the spirit of the invention nor conflict with the scope of the 25 appended claims.

Having thus fully described my invention what I claim as new and desire to secure by Letters Patent of the United States is:—

1. A rotary motor, comprising a bed, a 30 rotor casing upon said bed, a rotor within said casing, a shaft extending through said rotor, an exhaust port for said casing, a base formed upon said casing, a housing arranged upon said base, a hood arranged upon said 35 housing, a fuel chamber within said hood, fuel connections with said fuel chamber, a cylinder arranged within said housing, a piston operated in said cylinder, a compression chamber at each side of said piston, a 40 valve chamber formed between said compression chambers and said rotor casing, ports establishing communication between said compression chambers and said rotor casing, and a valve within said valve chamber for controlling the admission of the fuel 45 charge into said rotor casing.

2. A rotary motor, comprising a bed, a rotor casing upon said bed, a rotor within said casing, a shaft extending through said 50 rotor, an exhaust port for said casing, a base formed upon said casing, a housing arranged upon said base, a hood arranged upon said housing, a fuel chamber within said hood, fuel connections with said fuel chamber, a 55 cylinder arranged within said housing, a piston operated in said cylinder, a compression chamber at each side of said piston, a lower valve chamber formed between said compression chambers and said rotor casing, ports establishing communication between 60 said compression chambers and said rotor casing, a valve within said valve chamber for controlling the admission of the fuel charge into said rotor casing, a upper valve 65 chamber formed between said fuel chamber

and said compression chambers, ports for connecting said fuel chambers with said compression chambers, and a valve within said upper valve chamber for controlling the admission of fuel from said fuel chamber 70 into said compression chambers.

3. A rotary motor, comprising a bed, a rotor casing upon said bed, a rotor within said casing, a shaft extending through said rotor, an exhaust port for said casing, a base 75 formed upon said casing, a housing arranged upon said base, a hood arranged upon said housing, a fuel chamber within said hood, fuel connections with said fuel chamber, a cylinder arranged within said housing, a piston operated in said cylinder, a compression chamber at each side of said piston, a lower valve chamber formed between said compression chambers and said rotor casing, a valve within said valve chamber for controlling the admission to the fuel charge 80 into said rotor casing, an upper valve chamber formed between said fuel chamber and said compression chambers, ports for connecting said fuel chambers with said compression chambers, a valve within said upper valve chamber for controlling the admission of fuel from said fuel chambers into 85 said compression chambers, and means for operating said pistons and said valves. 90

4. A rotary motor, comprising a bed, a rotor casing upon said bed, a rotor within said casing, a shaft extending through said rotor, an exhaust port for said casing, a base 100 formed upon said casing, a housing arranged upon said base, a hood arranged upon said housing, a fuel chamber within said hood, fuel connections with said fuel chamber, a cylinder arranged within said housing, a piston operated in said cylinder, a compression chamber at each side of said piston, a lower valve chamber formed between said compression chambers and said rotor casing, a valve within said valve chamber for controlling the admission of the fuel 105 charge into said rotor casing, an upper valve chamber formed between said fuel chamber and said compression chambers, ports for connecting said fuel chambers with said compression chambers, a valve within said upper valve chamber for controlling the admission of fuel from said fuel chamber into 110 said compression chambers, means for operating said pistons and said valves, and means for alternately exploding the fuel charge in 115 the respective compression chambers at predetermined periods.

5. A rotary motor, comprising a bed, a rotor casing arranged upon said bed, a rotor within said casing, a shaft extending 125 through said rotor and said casing, an exhaust port for said casing, fuel inlet ports for said casing, a housing arranged upon said casing, a cylinder within said housing, a lower valve chamber arranged between 130

said cylinder and said rotor casing, a valve chamber arranged between said cylinder and a fuel chamber, a piston operating within said cylinder, compression chambers within said cylinder, a timing shaft arranged upon said motor, gearing connections between the driving shaft and said timing shaft, valves operated within said valve chambers, and connections between said timing shaft and

said piston and said valves for operating the same.

In testimony whereof I have signed my name to this specification in the presence of two subscribing witnesses.

JOHN DEAM KNEEDLER.
